UNITED STATES PATENT OFFICE.

JOHN H. QUIMBY, OF CONCORD, NEW HAMPSHIRE.

RAILWAY-SWITCH.

SPECIFICATION forming part of Letters Patent No. 275,518, dated April 10, 1883.

Application filed January 23, 1883. (No model.)

To all whom it may concern:

Be it known that I, JOHN HENRY QUIMBY, of Concord, in the county of Merrimac, of the State of New Hampshire, have invented a new and useful Improvement in Automatic Switches for Railways; and I do hereby declare the same to be described in the following specification and represented in the accompanying drawings, of which—

10 Figure 1 is a top view of a switch with its next adjacent main-track and siding rails provided with my invention, the nature of which is defined in the claims hereinafter presented. Fig. 2 is a side elevation of the switch-operative shaft and its movable handle. Fig. 3 is 15 a side elevation of a track with its manual-power switch-actuator. Figs. 4 and 5 are horizontal sections of the locking mechanism to be described, it being partially represented in 20 dotted lines in Fig. 1. Fig. 6 is a vertical and transverse section taken through the switch and its automatic actuator on an enlarged scale.

In the above-mentioned drawings, A A and 25 A' A' are the rails of the main track, while B B are those of the siding. The switch-rails are shown at C C, they being pivoted in the usual manner at the next adjacent ends of the track-rails A A and connected by cross-bars a, pivoted to them. These switch-rails, at their bases, 30 are embraced, as shown in Fig. 6, by the two arms b b of the automatic actuator D, such arms being pivoted to such actuator, which, formed as shown, is supported to slide lengthwise between parallel guides c c. Within the 35 said actuator, and in a cam-slot, d, formed in it, as represented, is a sectoral cam, e, which, with another sectoral cam, f, formed as shown, is fixed on a vertical shaft, g, duly pivoted in the rest and cap plates h i, arranged as shown. Between the said plates is another plate, k. The cam e is between the plates h and k, and the cam f is between the plates k and i, and also between parallel guides l l, arranged with 45 and forming part of the plate i, as shown. Between and against such guides, and arranged with the sectoral cam f in manner as represented, are two pitmen, E E', which at their outer ends are jointed to the shorter arms of two knee-levers, F G, formed and arranged 50 with respect to the main and siding track rails in manner as represented. The longer arms

of these levers are connected by a link, H, to which and to a short arm, m, projecting from a vertical shaft, n, a connecting-rod, o, is 55 jointed. The shaft n is the switch-operating shaft, it being duly supported in a standard, p. The shaft has pivoted to it a handle, q, to which and the shaft a spring, r, is applied, so as to force the handle upward into an upright 60 position. By taking hold of the handle and turning it down into a horizontal position a person can by means of it partially revolve the shaft, in order by manual power to cause the switch to be moved into alignment with 65 either the main-track or the siding rails, as occasion may require. On removing his hand from the handle it will, by its spring, be forced upward into an upright position, in order that it may not project from the shaft in a manner 70 to injure a person while standing near the shaft while the switch is operated automatically by a railway-car. Another knee-lever, l, arranged as shown, has one arm pivoted to the link H, there being pivoted to the other arm 75 a long rod, K, which goes through the switch and is pivoted to the shorter arm of a knee-lever, L. Such lever L, formed as represented, has its longer arm s on or about on a level with the top of one of the main-track rails A, 80 the shorter arm being extended across and beneath the said rail. Another arm, s', like the arm s, is secured adjacent to the opposite rail A on the outside of said rail, and connected with the arm s by a rod, t, jointed to both of said arms. 85 A railway-car truck is shown at M as having fulcrumed on one of its axles, at one end thereof, a lever, N, having its longer arm connected to a hand-lever, O, by a connecting-rod, u. Another such lever, N', is applied to the axle 90 at its other end, and connected by a rod, u', with another hand-lever, O'. As shown in the drawings, the ends of the arms s s' are bent, so that when said arms lie against the rails there is a space between them and such rails 95 at the ends of the arms, into which the lower ends of levers N N' enter, insuring certainty of action.

If we suppose the truck to be moving on the rails A A toward the switch, and the latter is 100 in alignment with the rails of the siding, and we desire to move the switch into alignment with the rails A' A' of the main track before the car may reach the switch, we have only

to move the lever N so as to throw its longer arm forward against the foremost of two stops, $v w$, projecting from the truck, such being to depress the shorter arm of the lever, in order to cause such shorter arm, while the truck may be advancing, to be carried between the rail A and the arm s of the knee-lever L , and thereby move the arm s away from the rail, and thus turn the lever L in a manner to cause the three knee-levers F , G , and I to be simultaneously turned, whereby the pitman E will be pushed forward and the other drawn backward. The pitman so pushed forward will be forced at its end against the cam f , and will cause such to partially revolve and revolve the cam e , which, acting in the slot d and against the actuator D , will move it so as to turn the switch into alignment with the rails $A' A'$. The pitman will next slide by the cam, and in so doing will lock it in position, so as to prevent it from being revolved the opposite way. The other sectoral cam will at the same time be firmly held in position, so as to prevent any accidental sliding of the actuator D . From the above it will be seen that each pitman and the two cams and the slotted actuator D will not only operate to move the switch in either direction, but lock it in position, so that it cannot accidentally get out of place when in alignment with either the main track or the siding. When the truck or car may be on the siding and running toward the switch, and the latter is in alignment with the rails $A' A'$, the wheel-flange of one side of the car will pass between a siding-rail and the next adjacent longer arm of the next adjacent knee-lever F , and press such arm inward away from the rail, whereby the switch will be moved into alignment with the siding in time for the car to run on the switch, and thence on the rails $A A$ of the main track. If the car is on the rails $A' A'$, and the switch may be in alignment with the siding, the knee-lever G will be operated by the flange of one of the car-wheels, so as to cause the switch to move and align with the rails $A' A'$. When the switch

is in alignment with the main-track rails $A A$ $A' A'$, as shown in the drawings, and the car is moving on the rails $A A$ in a direction toward the switch, and it is desirable to run onto the siding-track, such result can be accomplished by moving the lever N' , so as to depress its shorter arm into a position to enter between and force the arm s' away from the rail A , during such movement of the arm s' the switch will have been thrown into alignment with the siding-track.

I claim—

1. The combination, substantially as described, for automatically moving and locking the switch by the action of a wheel-flange of a car, such consisting in the slotted actuator D , the two sectoral cams e and f , the pitmen E and E' , and two knee-levers, F and G , and link H , all being connected and arranged with and applied to the switch and the main-track and siding rails, substantially and to operate as set forth.

2. The combination of the arm s' , rod t , the knee-lever L and rod K , and knee-lever I with the switch-operative mechanism composed of the slotted actuator D , sectoral cams e and f , pitmen E and E' , and two knee-levers, F and G , and link H , all being connected and arranged with and applied to the switch and the rails of the main and siding tracks, and to operate substantially as represented.

3. The car or truck provided with the levers N N' and mechanism for operating them, as described, in combination with the main-track and siding rails and the switch, and with the arm s' , rod t , knee-lever L , rod K , knee-lever I , and the switch-operative mechanism composed of the slotted actuator D , sectoral cams e and f , pitmen E and E' , and the two knee-levers, F and G , and link H , all being adapted and to operate substantially as set forth.

JOHN HENRY QUIMBY.
